Patented July 11, 1905.

UNITED STATES PATENT OFFICE.

OLIVER E. BARTHEL, OF DETROIT, MICHIGAN.

DESIGN FOR AN AUTOMOBILE-BODY.

SPECIFICATION forming part of Design No. 37,491, dated July 11, 1905.

Application filed March 16, 1904. Serial No. 198,513. Term of patent 3½ years.

To all whom it may concern:

Be it known that I, OLIVER E. BARTHEL, a citizen of the United States of America, residing at Detroit, in the county of Wayne and State of Michigan, have invented a certain new, original, and ornamental Design for an Automobile-Body, of which the following is a specification, reference being had therein to the accompanying drawings, forming a part thereof, in which—

Figure 1 is a perspective view of an auto-

mobile-body, showing my new design. Fig. 2 is a perspective view thereof looking from the front.

I claim—

The ornamental design for an automobile-body as shown.

OLIVER E. BARTHEL.
